POCKET

Theodore S. Tworoger, Johnstown, N. Y.

Application March 8, 1935, Serial No. 9,955

1 Claim. (Cl. 2—247)

This invention relates to new and useful improvements in a garment pocket.

The invention has for an object the construction of a garment pocket having two pocket sections with mouth openings at right angles to each other.

More particularly, the invention contemplates the construction of a pocket with a top opening, and a pocket section in the front material of the pocket and having a side mouth opening.

Still further the invention proposes the construction of a garment pocket which is characterized by a front layer of material attached along continuous lines to a rear layer of material forming a pocket, and arranged with an opening in the front layer for forming the mouth of the pocket, and an intermediate layer of material attached at its edges to the front material at one side of said mouth opening and also forming a pocket, and the front material being formed with a second opening constituting the mouth for the second pocket.

A still further object of the invention is the construction of another pocket upon the intermediate layer arranged with strips on the opposed sides of the mouth opening thereof adapted to interlock on lateral movements so that one hand must be placed in each of the two pockets, previously mentioned, for the opening and closing of the said pocket.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:—

Fig. 1 is a front elevational view of a windbreaker jacket with pockets constructed according to this invention.

Fig. 2 is a fragmentary enlarged detailed view of one of the pockets shown in Fig. 1.

Fig. 3 is a sectional view taken on the line 3—3 of Fig. 2.

Fig. 4 is a horizontal sectional view taken on the line 4—4 of Fig. 2.

Fig. 5 is a view similar to Fig. 3 but illustrating a vertical sectional view of a garment pocket constructed according to another embodiment of the invention.

Fig. 6 is a fragmentary elevational view looking in the direction of the line 6—6 of Fig. 5.

Fig. 7 is a fragmentary enlarged sectional view taken on the line 7—7 of Fig. 6.

In Fig. 1 a windbreaker 10 is illustrated formed with pockets 11 constructed according to this invention. Each of these pockets has a pair of pocket sections as hereinafter fully described in detail.

In Figs. 2—4 inclusive a detail of one of the pockets 11 is shown. The pocket comprises a front layer of material 12 attached along a continuous line 13^a, 13^b, 13^c and 13^d to a rear layer of material 14 forming a pocket 15. The front layer 12 is formed with a pocket opening 16 which is normally closed with a flap 17. An intermediate layer of material 18 is attached at its edges to the front material 12 at one side, namely beneath said pocket opening 16 and forms a second pocket 19. This latter-mentioned pocket is formed with a pocket opening 20 in the front material 12.

The front layer of material 12 illustrated on the drawing consists of an upper section 12^a secured together by stitches 13^d with a lower section 12^b.

The continuous line 13^a, 13^b, 13^c and 13^d comprises lines of stitches at right angles to each other dividing off a rectangular area. The line of stitches 13^b serves to secure the upper edge of the flap 17 together with the upper edge of the material of the front layer 12 at the pocket opening 16, and the upper edge of the rear layer 14. The lines of stitches 13^a and 13^c serve to attach the sides of the rear layer 14 and the intermediate layer 18 together with the front layer 12. A double line of stitches 13^e extends between the lines of stitches 13^b and 13^d merely for decorative purposes to give the finished jacket the appearance that the pockets 11 are of the same width as the flaps 17.

The jacket 10 is also equipped with a lining 22. This lining is secured along one side 22' to a flange 23 extended along one edge of the front opening of the jacket. Hook fasteners 24 are secured upon the edge of the jacket between the lining 22 and a bent edge of the front material 12^a. This line of hook fasteners is adapted to engage with a complementary line on the opposed edge of the front opening of the jacket (not shown on the drawing) by which the front of the jacket may be opened and closed.

The mouth opening 20 is finished by a pair of opposed strips 25 attached upon the opposed sides of the mouth opening on the inner faces thereof. These reinforcement strips may be made of leather piping or any suitable fabric. A shielding strip 26 is secured on the intermediate layer 18 immediately behind the mouth opening 22 so as to shield and reinforce the intermediate layer 18 at 55

the area of the mouth opening 20 to prevent rapid wearing out of the intermediate layer at this area. The rear layer 14 is composed of an upper section 14^a and a lower section 14^b secured together at 5 the junction 14^c. The lower end of the material of the lower section 14^b is bent upwards and forms a lower section 18^a of the intermediate section 18.

This bent up end of the intermediate layer connects at the junction 18^b with a top section 18^c. This arrangement is such that when the lower section of the pocket 15 becomes torn, the section composed of the parts 14^b and 18^a, may be readily removed and replaced. The lower edge of the pocket 15 is reinforced with a line of 10 stitches 27. The stitches 18^b pass through the front layer 12^a, the flap 17 and the layer 14^a. The flap 17 consists of outer material 17^a and lining material 17^b secured together along the edges by stitches 28. The flap 17 is formed 15 with a buttonhole opening 29 engageable with a button 30 attached upon the outer side of the front material 12.

In Figs. 5 and 6 a modification of the invention has been disclosed which distinguishes from the 25 previous form merely in the construction of the intermediate layer of material 18'. More particularly, a third pocket 38^a is mounted on this layer and is openable and closable in a particular manner. More specifically, the intermediate layer 18^a 30 is formed with a pocket opening having strips 31 and 32 secured upon the opposed sides thereof. These strips have inter-engageable elements 33 adapted to connect with each other upon lateral motion. Tongues 33^a project from the strip 31 and are adapted to be laterally placed 35 into receiving recesses formed in the side of the strip 32. A pocket panel 34 is attached at its top edge 34^a upon the strip 31 and is secured at the remaining three sides by stitches 35 to the material of the intermediate layer 18'.

40

In order to open and close the mouth of the pocket 38^a it is necessary that one hand be engaged in the pocket 15, and the other hand be engaged in the pocket 18, and then the strips 31 and 32 be moved laterally relative to each other, either 5 to open or close the pocket, depending merely on the direction of the motion of these strips.

When moved together, the pocket is closed. In other respects this form of the invention is identical to the previous form and the identical parts 10 may be recognized by the same reference numerals.

While I have illustrated and described the preferred embodiment of my invention, it is to be understood that I do not limit myself to the 15 precise construction herein disclosed and the right is reserved to all changes and modifications coming within the scope of the invention as defined in the appended claim.

Having thus described my invention, what I 20 claim as new, and desire to secure by United States Letters Patent is:—

In a pocket construction for garments, a rear layer of material having its top edge attached to the inner face of the garment material, an intermediate layer of material having its sides and bottom coinciding with the sides and bottom of the rear layer and being attached thereto, the top edge of the intermediate layer being below the top edge of the rear layer and forming an opening, a strip of reinforcing material attached to the outer face of said intermediate layer along one side, an outer layer of material attached along its edges to said intermediate layer and strip, said outer layer having a substantially 35 vertical opening therein over said reinforcing strip and two-ply material attached along the edges of said opening.
